ABSTRACT: Apparatus and method for securing caps on the ends of cores, drums, and the like. A novel pivotally mounted roller performs a longitudinally advancing spinning action upon the skirt of a pre-applied cap. Upon withdrawal of the spinning head the roller automatically imparts a narrow peripheral crimp to the spun down skirt.

APPARATUS AND METHOD FOR CAPPING A CYLINDRICAL TUBE

BACKGROUND OF THE INVENTION

This invention relates to the field of capping cylindrical tubes. In general, the caps involved may be covers such as end closures for drums or annular reinforcing rings for the ends of fibrous cores such as are used in rolls of paper or the like. In either case it is usually desirable to slip the cap over the end of the tube and thereafter to secure it in place by lateral deformation against the tube wall. Typical prior art apparatus for performing this operation is shown in Pottle U.S. Pat. No. 2,403,998 and Magill U.S. Pat. No. 2,633,095.

It will be observed that the prior art devices are limited to rather simple forming operations and moreover are cumbersome to use. Frequently it is desirable to secure the cap by general deformation over a large skirt area with a narrow peripheral crimp for anchoring. Heretofore there has been no simple practical tool for accomplishing this compound action. In general, it has been necessary to employ a pair of independently operated tools; one for general deformation and the other for crimping.

SUMMARY OF THE INVENTION

This invention provides an apparatus and method for performing the aforesaid deformation and crimping operations simply and efficiently by rotating the tube about its longitudinal axis and then merely advancing and withdrawing a roller which is mounted on a control bar in a novel pivotal fashion. In the preferred embodiment there is employed a cap with a flared skirt which is spun down against the tube by the longitudinally advancing roller. At the end of the spinning action, the withdrawal of the control bar causes the roller to pivot away from the cap, but with a swinging motion which initially moves the roller crimpingly inward toward the cap. The pivotal movement, as above described, is produced by mounting the roller on a foot which is in turn pivotally connected to the control bar. Crimping is achieved by locating the pivot point longitudinally forward of the roller working surface; "forward" being the direction of roller longitudinal advance during the general spinning action. The mechanical principles therein involved are more fully explained in the drawings and the description of the preferred embodiment which follow.

BRIEF DESCRIPTION OF THE DRAWINGS

FIG. 1 is an illustration in section of a preferred embodiment showing a pair of cooperating rollers simultaneously spinning down the inside and outside skirts of an annular cap.

FIG. 2 is an enlarged diagrammatic illustration of a crimping operation.

DESCRIPTION OF THE PREFERRED EMBODIMENT

The preferred embodiment for this invention is generally shown in FIG. 1 wherein a cylindrical fiber core 1 has been cut away to expose an inserted inner tool 2 which extends through an aperture in chuck 5 for cooperation with outer tool 3. Tools 2 and 3 are shown working on an annular cap 4 which has been seated at the end of core 1 by the action of chuck 5 working against a tail stock (not shown). Cap 4 is of the type generally shown in Dodge U.S. Pat. 1,358,531 but modified for ease of seating by flaring the inner skirt as at 6 and the outer skirt as at 7. Tools 2 and 3 are each comprised of a control bar 8, a foot 9, and a roller 10. Pivot pins 11, provide pivotal support for feet 9, thereby enabling feet 9 to swing away from their respective working surfaces as indicated by the broken lines of FIG. 1. The swinging action is rotationally limited in the working-surface direction by walls of channels which are cut medially into feet 9 thereby permitting feet 9 to straddle control bars 8. As shown in partially cut away fashion on tool 3, wall 12 bears against the edge of control bar 8 during longitudinal advance of roller 10.

While the aforesaid rotationally limited pivotal action is an important aspect of this invention, the means for limiting the pivotal rotation are a mere matter of choice. For instance, the function of wall 12 could be well served with a pin, lug, or other projection.

In operation core 1 is rotated about its longitudinal axis while tools 2 and 3 simultaneously perform longitudinally advancing spinning actions against flared skirts 6 and 7 thereby bringing cap 4 into intimate contact with core 1. When tools 2 and 3 reach the ends of their longitudinal strokes, the spinning action is complete and the crimping action commences.

FIG. 2 illustrates the mechanics of the crimping action by showing the tool of this invention at two different positions during crimping. The solid lines represent the tool at the end 15 of the aforesaid longitudinal stroke and the broken lines represent the tool at that point where the crimping action is maximum. The crimping action as shown in FIG. 2 is representative of the operation of either tool. Corresponding to the two 20 tool positions, the wall 13 is shown solid (spun down) and broken (crimped).

Crimping is begun by applying a withdrawal force to control bar 8 while maintaining roller 10 in contact with wall 13. This sets up a frictional resisting force F acting in the indicated 25 direction and tending to rotate foot 9 clockwise about pivot pin 11. However, since the point of pivotal rotation is longitudinally forward of the roller working surface, the effect of force F is to urge roller 10 toward wall 13. It will be appreciated that this is a 3 dimensional operation because continuing rotation of the core causes movement of wall 13 in a direction which is locally perpendicular to the plane of FIG. 2. F is essentially a static frictional force because roller 10 spins about its mounting axis to give its working surface a circumferential velocity matching the spinning velocity of wall 13.

As shown in FIG. 2, movement of roller 10 toward wall 13 is resisted by a normal force N acting in the indicated direction. Forces N and F are in fact reacting forces automatically set up to oppose a driving force (not shown) which, during crimping, is transmitted by control bar 8 through pivot pin 11 and on out to roller 10. It should be observed that N is a continuously 30 present force which is essentially constant during the spinning action and variable during crimping. It is apparent that clockwise rotation of foot 9 cannot occur unless the sum of the clockwise moments about pivot pin 11 exceeds the sum of the counterclockwise moments about the same point. In 35 mathematical form the requirement is stated as follows:

$$Fr \cos \theta > Nr \sin \theta$$

where r is the radius and θ is the lead angle as both are illustrated in FIG. 2.

The above requirement imposes a limitation upon the use of the inventive tool. This can be seen by observing that F and N have magnitudes which are directly proportional. That is:

$$F = \mu N$$

where μ is the coefficient of friction of roller 10 against wall 13. Upon combining the above equations and performing other indicated operations, the limitation becomes:

$$\mu > \tan \theta$$

This means that for a given lead angle there can be no crimping action unless the coefficient of friction is above some 65 minimum value. If the stated condition is satisfied, then the tool will move as illustrated in FIG. 2 and a crimp will be achieved. Upon completion of the crimp, foot 9 will swing clear of wall 13 and follow control bar 8 through the 70 withdrawal stroke. If μ has a magnitude less than the minimum value stated by the above equation, then the rotation of foot 9 will be resisted by excessive counterclockwise moments, and the foot will merely follow the withdrawal of control bar 8 without crimping wall 13.

75 As far as the inventive apparatus is concerned, the above

discussion merely outlines restrictions on use. However, this invention contemplates a process as well as an apparatus. For the process there is a necessary limitation which is somewhat the reverse of the restriction upon the apparatus. Thus, if it is desired to practice this invention to crimp a cap of some given material, then it becomes necessary to select a roller of any suitable material, and, upon completion of the usual spinning action, to apply a pivotally supported withdrawal force. The mechanics of the crimping operation require that the point of pivotal support be longitudinally forward of the roller working surface and furthermore positionally restricted such that:

$$\theta < \tan^{-1} \mu$$

In the preferred embodiment of this invention the lead angle θ has a value of about 10 degrees. Application of the appropriate equation indicates that the preferred apparatus may be used in any situation wherein μ has a value no less than about 0.176. When working with metal on metal in a clean condition, the coefficient of friction is generally always above that value. For steel on steel μ has a value of about 0.53 which is well above the computed minimum. Under lubrication conditions, however, μ may be expected to drop to a value of around 0.1 or less. This means that the preferred embodiment should be used under clean nonlubricated conditions.

Alternatively, for practicing the inventive process to crimp a clean steel cap with a clean steel roller, the coefficient of friction assumes a fixed value of 0.53, and there arises a lead angle limitation. Application of the appropriate equation discloses that under the stated conditions θ may be no greater than about 28 degrees.

As a matter of engineering practice, therefore, the apparatus of this invention preferably should be designed with a lead angle less than about 28 degrees. While being positioned to accommodate this preference, the pivot pin of the preferred embodiment may be further positioned to fix the amount of crimp desired. It is easily shown that the crimp Δ is controlled by fixing the radius r and the lead angle θ in accordance with the following equation:

$$\delta = r - r \cos \theta$$

We claim:

1. In a machine for capping a cylindrical tube, cap deforming apparatus comprising:
45 a roller for peripheral rolling contact against a wall of a cap;

a foot for supporting the roller during said contact; and a longitudinally moveable control bar supporting the foot by rotationally limited pivotal connection thereto; the rotational limit for said pivotal connection being fixed to support the foot for a longitudinally advancing cap deforming action, and the point of pivotal connection being positioned longitudinally forward of the roller working surface thereby swinging said working surface crimpingly toward the cap upon application of a withdrawal force to the control bar.

2. Cap deforming apparatus according to claim 1, and further comprising a pivot pin for provision of said pivotal connection.

3. Cap deforming apparatus according to claim 2 said foot 15 being provided with a medially extending channel for straddling the control bar and providing the rotational limit for said pivotal connection.

4. In a machine for capping a cylindrical tube a pair of cap deforming apparatus each of said apparatus being constructed 20 according to claim 3, one of said apparatus being mounted for deformation of the interior skirt of an annular cap and the other said apparatus being mounted for cooperating deformation of the exterior skirt of the same annular cap.

5. A pair of apparatus according to claim 4, each of said apparatus having its pivot pin located for a lead angle less than about 28 degrees.

6. The method of reinforcing a resilient cylindrical tube comprising the steps of:

1. seating at an end of said tube a metal cap provided with a flared skirt;

2. rotating the tube about its longitudinal axis; and

3. while rotating the tube:

a. urging a metal deforming roller into rolling peripheral contact with the cap; and

b. while maintaining said rolling peripheral contact:

i. advancing the roller in the longitudinal direction thereby deformably removing the flare from the flared skirt and forcing the cap into intimate contact with the tube; and

ii. thereafter longitudinally withdrawing the roller by applying a pivotally supported withdrawal force at a point longitudinally forward of the roller working surface but with a lead angle the tangent of which is less than the numerical value of the coefficient of friction of the roller against the cap thereby providing a frictionally induced pivotal crimping action.
